United States Patent Office

Des. 215,808
Patented Nov. 4, 1969

215,808

JOINT FINISHER

Christopher C. Hardy, P.O. Box 5371, Heland Park
Station, Panama City, Fla. 32401

Filed Dec. 28, 1967, Ser. No. 9,969

Term of patent 14 years

Int. Cl. D8—02

U.S. Cl. D8—45

FIG. 1 is a perspective view of my new design for a joint finisher.

FIG. 2 is a side view in elevation of the joint finisher shown in FIG. 1.

FIG. 3 is a top plan view of the joint finisher shown in FIG. 1.

FIG. 4 is a bottom plan view of the joint finisher shown in FIG. 1.

FIG. 5 is an end view of the joint finisher shown in FIG. 2 looking from the left side thereof.

FIG. 6 is an end view of the joint finisher shown in FIG. 2 looking from the right side thereof.

FIG. 7 is a perspective view of a modified form of my new design for a joint finisher.

FIG. 8 is a sectional view taken on line 8-8 of FIG. 7 as indicated by the arrows.

FIG. 9 is a perspective view of another modified form of my new design for a joint finisher.

FIG. 10 is a sectional view taken on the line 10-10 of FIG. 9 as indicated by the arrows.

I claim:

The ornamental design for a joint finisher, as shown.
